[57] CLAIM

The ornamental design for a coated masonry building block, as shown and described.

DESCRIPTION

FIG. 1 is an isometric view of one embodiment of our new design for coated masonry building block;

FIG. 2 is a top view of the embodiment of FIG. 1;

FIG. 3 is a bottom view of the embodiment of FIG. 1;

FIG. 4 is a side elevational view of the embodiment of FIG. 1;

FIG. 5 is a front elevational view of the embodiment of FIG. 1;

FIG. 6 is a rear elevational view of the embodiment of FIG. 1;

FIG. 7 is an isometric view showing a second embodiment of our new design for coated masonry building block;

FIG. 8 is a top view of the embodiment of FIG. 7;

FIG. 9 is a bottom view of the embodiment of FIG. 7;

FIG. 10 is a side elevational view of the embodiment of FIG. 7;

FIG. 11 is a front elevational view of the embodiment of FIG. 7;

FIG. 12 is a rear elevational view of the embodiment of FIG. 7;

FIG. 13 is an isometric view showing a third embodiment of our new design for coated masonry building block;

FIG. 14 is a top view of the embodiment of FIG. 13;

FIG. 15 is a bottom view of the embodiment of FIG. 13;

FIG. 16 is a side elevational view of the embodiment of FIG. 13;

FIG. 17 is a front elevational view of the embodiment of FIG. 13;

FIG. 18 is an isometric view showing a fourth embodiment of our new design for coated masonry building block;

FIG. 19 is a top view of the embodiment of FIG. 18;

FIG. 20 is a bottom view of the embodiment of FIG. 18;

FIG. 21 is a side elevational view of the embodiment of FIG. 18; and,

FIG. 22 is a front elevational view of the embodiment of FIG. 18.
